(57) **CLAIM**

The ornamental design for a vacuum insulated beverage tumbler, as shown and described.

DESCRIPTION

FIG. 1 is a top front perspective view of a vacuum insulated beverage tumbler, showing my new design; FIG. 2 is a front elevational view of FIG. 1 thereof; FIG. 3 is a rear elevational view of FIG. 1 thereof; FIG. 4 is a left side elevational view of FIG. 1 thereof; FIG. 5 is a right side elevational view of FIG. 1 thereof; FIG. 6 is a top plan view of FIG. 1 thereof; and, FIG. 7 is a bottom plan view of FIG. 1 thereof. The broken lines indicate unclaimed portions of the design and form no part of the claimed design.

1 Claim, 7 Drawing Sheets
